United States Patent Office

Des. 183,644
Patented Oct. 7, 1958

183,644

MAGNETIC RECORD MAGAZINE OR SIMILAR ARTICLE

Roberto O. Alvarado, Miraflores, Peru

Application February 11, 1957, Serial No. 44,825

Term of patent 7 years

(Cl. D26—14)

FIG. 1.

FIG. 2.

Fig. 1 is a front perspective view of a magnetic record magazine or similar article, showing my new design; and Fig. 2 is a rear perspective view.

I claim:

The ornamental design for a magnetic record magazine or similar article, substantially as shown.
